[57] CLAIM

The ornamental design for a television receiver or similar article, substantially as shown and described.

DESCRIPTION

FIG. 1 is a front, top and right side perspective view of a television receiver or similar article showing our new design;

FIG. 2 is a rear, bottom and left side perspective view; and

FIG. 3 is a view similar to FIG. 1 of the receiver with the channel selection and tuning control unit housing transposed from above to below the picture tube housing.

FIG. 1

FIG. 2

FIG. 3
